CONTROL APPARATUS

Milan A. Neslin, Scotia, N.Y., assignor to General Electric Company, a corporation of New York
Filed Feb. 5, 1962, Ser. No. 170,895
6 Claims. (Cl. 214—135)

This invention relates to an automatic control for controlling the digging operation of a shovel.

Large stripping and loading shovels are used extensively for digging operations. The initial cost of shovels is large and the operating expense is appreciable. Economic considerations require that they be used as efficiently as possible. One of the primary problems in operating a shovel efficiently is in consistently filling the dipper of the shovel during the digging operation so as to achieve the smallest average digging time over an operating shift.

It is an object of this invention to provide a new shovel control for controlling the digging operation of a shovel so that the dipper is consistently filled in the smallest average time over an operating shift.

Two motions give primary control of the digging of the dipper in the bank. The crowd motion moves the dipper into and out of the bank and the hoist motion moves the dipper upwards. The speed at which the dipper is moved upwards is termed the hoist speed and the force which is applied to move the dipper upwards is termed the hoist pull. The dipper digs in the bank and is loaded as the dipper is moved upwards and as the crowd motion moves the dipper into the bank. Prime movers, such as electric motors, supply the power for the hoist motion and the crowd motion. These prime movers and the mechanical elements of the shovels are designed within specific limits for a given excavator rating. After the upward hoist pull of the hoist motion exceeds a design value, the hoist speed must be decreased to avoid exceeding the design limits.

In the drawings, FIGURE 1 shows hoist speed plotted against hoist pull to show the limits and characteristics of a typical hoist motion. The hoist pull may be increased at the top speed of 7 until the hoist develops a pull of 4 at point A. From point A, as the hoist pull is increased, the hoist speed decreases until finally the dipper will be stalled in the bank.

The hoist pull necessary to move the dipper upwards is a function of how far into the bank the dipper has been moved by the crowd motion and also the crowd force applied. Thus, as the dipper is moved farther into the bank and more crowd force is applied, more hoist pull is required. After the hoist pull reaches point A on the hoist motion curve in FIGURE 1, the hoist speed decreases as the hoist pull is increased.

For efficient digging, the dipper should remain in the bank while moving upwards until it is full. The operator judges the shape and conditions of the bank and applies the proper crowd motion and hoist motion to the dipper to emerge from the bank with a full dipper. For instance, for a high bank where the dipper may travel a considerable vertical distance after it is entered into the bank, the dipper may be entered a short distance into the bank by the crowd motion and be hoisted at the fastest hoist speed. The required hoist pull may not be great and the digging operation could be about point A of the hoist motion curve shown in FIGURE 1.

On the other hand, where the bank is relatively low, the dipper may be entered a greater distance into the bank and a greater hoist pull may be required to lift the dipper. Under these conditions, the hoist speed could be less and the digging operation may take place about point C on the hoist motion curve shown in FIGURE 1.

2

The operator must continually change settings on the two separate crowd and hoist regulators during the digging operation to accommodate the changing conditions of the bank and shovel. The rapidly changing conditions may cause the operator to misjudge the crowd and hoist motion forces and speeds necessary to emerge with a full dipper. For instance, the dipper may be entered too far into the bank so that too much hoist pull is used at a slow speed and the dipper may continue to be pulled through the bank after it is already loaded. Such misjudgements are not uncommon and the time required to fill the dipper varies, resulting in a less efficient digging operation.

Another object of this invention is to provide apparatus for automatically controlling the crowd and hoist motions of the dipper of a shovel.

According to this invention the digging of the dipper of a shovel is controlled automatically. As the crowd motion enters the dipper into the bank and the hoist motion lifts the dipper, a hoist motion signal corresponding to an actual hoist motion function is compared with a reference signal. The reference signal corresponds to a desired hoist motion. The crowd motion is adjusted automatically according to the difference between the reference hoist motion signal and the actual hoist motion signal.

The reference hoist motion signal may be changed according to the particular bank that the shovel is digging in so that the dipper is consistently loaded and so as to obtain the shortest average digging time.

The novel features of the invention are set forth with particularity in the appended claims. The invention itself, however, both as to its organization and method of operation, together with further objects and advantages thereof, may best be understood by referring to the following description and the accompanying drawings.

In the drawings:

FIGURE 1 shows the hoist motion curve with the hoist speed plotted against the hoist pull.

FIGURE 2 shows a large stripping shovel with the major elements of the shovel.

FIGURE 3 is a block diagram of the control circuitry for controlling the crowd and hoist motions of the shovel.

FIGURE 4 is a schematic of the circuitry for the automatic regulation circuit.

For an understanding of the configuration and general operation of a stripping or loading shovel, reference should be made to FIGURE 2. The machinery house 15 is rotatable on a roller circle 17 secured to a lower frame 19. Crawlers 21 secured to lower frame 19 may be actuated to propel the shovel. Dipper 23, secured to dipper handle 25, may be moved in a crowd motion into and out of the bank 27 as the crowd pinion 29, secured to the boom 31 or to other structures supported by the upper frame, is actuated by the crowd motor 33 and engages the crowd rack 35 secured to the dipper handle 25. The dipper 23 is moved upwards as hoist cable 37 threaded through the boom point pulley 38 at the tip of boom 31 and the gantry pulley 39 on the gantry 40 is wound on the hoist drum 41 when it is rotated by the hoist motor 42.

The dipper 23 is entered into the bank 27 by a combination of hoist and crowd motion and then the dipper is pulled upwards by the hoist motion through the bank until it is loaded. After the dipper is loaded, the machinery house 15 rotates on the roller circle 17, moving the loaded dipper to a predetermined point where the load is emptied onto a discharge pile or into a truck.

Refer now to FIGURE 3 for a description of the electrical apparatus. Hoist generator 46 and crowd generator 47 are controlled by hoist regulator 48 and crowd regulator 49, respectively. Hoist drum 41 and crowd pinion

29, respectively, may be rotated in a standard manner as determined by the position of hoist controller 43 and crowd controller 44, respectively.

The motor generator sets and regulators are standard commercial products widely used in shovels. The hoist motion and crowd motion may be controlled independently, as has been the prior practice, by the hoist and crowd controllers, respectively.

The shovel is set to dig automatically by moving switch 59 of automatic regulator 50 from the "HAND" position to the "AUTO." At some time before the automatic dig control is actuated, the operator examines the bank and preselects the desired automatic digging speeds. The automatic digging speeds are selected by varying the automatic reference signal. The automatic reference signal may be varied while digging by some conventional means such as variable resistance 57 and switch 58. The digging speed is established by loading of the hoist motion and the limits of the hoist motion shown in FIGURE 1. Therefore, the operator essentially selects the points on the graph of FIGURE 1 at which he chooses to dig automatically by varying resistance 57. The automatic dig control is actuated by moving both the hoist and crowd controllers to a specific position which energizes the hoist and crowd regulators for automatic operation.

The proper point on the hoist motion limits curve may be determined by the individual experience of the operator or by reference to a prepared chart. The chart would take into consideration such factors as height of bank, type of material in bank, consistency of material, shape of the bank and preparation of the bank by drilling, blasting or other means.

For purposes of this description, four points on the hoist motion curve, A, B, C and D are shown in FIGURE 1. Reference signal switch 59 may be switched from "HAND" to "AUTO". Points A, B, C or D on variable resistance 57 may be selected by switch 58. Variable resistance 57 may be continuously variable to select intermediate points between A, B, C and D.

Prior to starting automatic digging, switch 58 is set at the desired point on variable resistance 57 and switch 59 is moved from "HAND" to "AUTO". Dipper 23 in FIGURE 2 is lowered toward the bottom of bank 27 and is entered into the bank under manual control of the operator. The automatic control is actuated and a signal is derived from the current flowing from hoist generator 47 in FIGURE 3 to hoist motor 42. This hoist signal is a function of the hoist motion and the point on the hoist motion curve in FIGURE 1 where the hoist motion is operating. This hoist motion signal may also be derived from the hoist rope pull, the hoist motor or hoist drum speed, or the voltage from the hoist generator. Reference signal switch 58 may be connected to a variable resistance 57 and is continuously variable to provide a reference signal indicating the desired point on the hoist motion curve at which the hoist motion should operate.

Under automatic control the desired hoist motion signal and the actual hoist motion signal are compared in automatic regulator 50 which produces a signal indicating the magnitude and polarity of the difference. The difference signal is applied to crowd regulator 49 to cause the crowd motion to force harder, ease up, or maintain the same force on the dipper in the bank.

The comparison between the desired and actual hoist motion is continuous, causing the crowd motion to be changed depending on how close to the desired hoist motion the actual hoist motion is.

As the dipper continues to be moved upward through the bank, an experienced operator may change the position of the reference signal switch to insure that the dipper will emerge from the bank fully loaded. Also, the reference signal may be programmed to automatically change.

An automatic control such as described will insure that the dipper of a shovel will be filled consistently in the smallest average digging time over an operating shift.

An automatic regulator circuit is shown in FIGURE 4 which may be used as the automatic regulator circuit shown as block 50 in FIGURE 3. In this particular embodiment the hoist motion signal is the hoist motor voltage taken from the terminals of hoist motor 42. If hoist motor current is used as the hoist motion signal, the hoist motion signal is taken as the voltage across the commutating and compensating fields.

The hoist motion signal in the form of the hoist motor voltage with resistors 52 and 53 causes a current flow through winding 51 of magnetic amplifier 54. The reference signal representing the desired hoist motion is provided by a voltage source and reference winding 60 in series with variable resistance 57 which may be a rheostat. Rheostat 57 is shown with four definite points, A, B, C and D to correspond with points A, B, C and D on the hoist motion curve in FIGURE 1. For finer adjustment, switch 58 may be connected to any point on rheostat 57.

The ampere-turns of winding 51 oppose the ampere-turns of the reference winding 60. The output of magnetic amplifier 54 is proportional to the difference between the reference ampere-turns and the hoist motion ampere-turns. The feedback circuit of resistor 63, capacitor 62, and winding 61 is for stabilizing.

The output of magnetic amplifier 54 is amplified by magnetic amplifier 64. Winding 66 and resistor 65 develop ampere-turns proportional to the output of magnetic amplifier 54. Resistor 70 and capacitor 71 provide stabilizing.

The output voltage of magnetic amplifier 64 produces a current through resistor 72 and amplidyne winding 73. The ampere-turns of winding 73 oppose the ampere-turns of winding 75. The output of amplidyne 76 is proportional to ampere-turns of winding 73.

If the hoist motor voltage is too high, the output of magnetic amplifier 54 is reduced. This, in turn, reduces the output of magnetic amplifier 64, which allows the voltage of amplidyne 76 to increase in the direction to cause the dipper to enter further into the bank.

If hoist motor current is used, the polarity connections are made such that the output of magnetic amplifier 54 is increased if the motor current is too high.

If motor speed is used for the hoist motion signal, a voltage is taken from a tachometer connected on the hoist motor shaft. Its polarity is taken the same as for motor terminal voltage.

While this invention has been explained and described with the aid of a particular embodiment thereof, it will be understood that the invention is not limited thereby and that many modifications will occur to those skilled in the art. It is therefore contemplated by the appended claims to cover all such modifications as fall within the scope and spirit of the invention.

What is claimed is:

1. Apparatus for automatically controlling the hoist and crowd motions of a dipper of a shovel during a digging operation including:

(a) means for sensing the hoist motion of the dipper during the digging operation and developing a signal corresponding to the actual hoist motion,

(b) and control means connected to said sensing means responsive to variations in the actual hoist motion relative to a reference hoist motion to cause the crowd motion to be adjusted so that the actual hoist motion corresponds to the reference hoist motion.

2. Apparatus for automatically controlling the hoist and crowd motions of a dipper of a shovel during digging operations including:

(a) means for sensing the hoist motion of the dipper during digging operations and developing a signal corresponding to the actual hoist motion,

(b) means for producing a reference signal corresponding to a predetermined desired hoist motion,

(c) and means for generating a signal corresponding to the difference between said actual hoist motion signal and said reference signal to cause the crowd motion to be adjusted so that actual hoist motion corresponds to the predetermined desired hoist motion.

3. Apparatus for automatically controlling the hoist motion of the dipper of a shovel during a digging operation including:

- (a) means for developing a signal corresponding to the actual hoist motion,
- (b) means for producing a reference signal corresponding to a predetermined desired hoist motion,
- (c) means for generating a signal corresponding to the difference between said actual hoist motion signal and said reference signal to cause the actual hoist motion to be adjusted to the predetermined desired hoist motion,
- (d) and means for changing said reference signal.

4. Apparatus for automatically controlling the hoist and crowd motions of a dipper of a shovel during digging operations including:

- (a) means for sensing the hoist motion of the dipper during digging operations and developing a signal corresponding to the actual hoist motion,
- (b) means for producing a reference signal corresponding to a predetermined desired hoist motion,
- (c) means for generating a signal corresponding to the difference between said actual hoist motion signal and said reference signal to cause the crowd motion to be adjusted so that actual hoist motion corresponds to the predetermined desired hoist motion,
- (d) and means for changing said reference signal.

5. Apparatus for automatically controlling the hoist and crowd motions of a dipper of a shovel during digging operations including:

- (a) means for starting the hoist motion of a dipper of a shovel,
- (b) means for sensing the hoist motion of the dipper during the digging operation and developing a signal corresponding to the actual hoist motion,
- (c) means for producing a reference signal corresponding to a predetermined desired hoist motion,
- (d) means for generating a difference signal corresponding to the difference between said actual hoist signal and said reference signal,
- (e) and means for controlling the crowd motion responsive to said difference signal for causing the

crowd motion to be adjusted so that the actual hoist motion corresponds to the desired hoist motion.

6. Apparatus for automatically controlling the hoist and crowd motions of a dipper of a shovel during digging operations including:

- (a) means for starting the hoist motion of a dipper of a shovel,
- (b) means for sensing the hoist motion of the dipper during the digging operation and developing a signal corresponding to the actual hoist motion,
- (c) means for producing a reference signal corresponding to a predetermined desired hoist motion,
- (d) means for generating a difference signal corresponding to the difference between said actual hoist signal and said reference signal,
- (e) means for controlling the crowd motion responsive to said difference signal for causing the crowd motion to be adjusted so that the actual hoist motion corresponds to the desired hoist motion,
- (f) and means for varying said reference signal according to a desired hoist motion.
